[57] ABSTRACT

An improvement in the production of low mineral content fuel by coal liquefaction processes which yield as a primary product a mixture of liquid and solids a part of

which are suspended in the liquid whereby the separation of the suspended solids is facilitated by the addition of an effective amount of a suitable chelating agent to the mixture. The chelating agent is optionally added as a solution of the chelating agent in a suitable solvent and desirably is present in an amount from about 100 to about 150% of the stoichiometric amount required to react with the suspended solids in the mixture.
